UNITED STATES PATENT OFFICE.

ARNOLD B. OGDEN AND ERVIN WILLIAM WEIGAND, OF JEFFERSON CITY, MISSOURI.

SELF-SEALING INSTANTANEOUS-OPENING ENVELOPE.

Application filed February 28, 1922. Serial No. 540,057.

To all whom it may concern:

Be it known that we, ARNOLD B. OGDEN and ERVIN WILLIAM WEIGAND, citizens of the United States, and residing at Jefferson City, county of Cole, and State of Missouri, have invented a new and useful Self-Sealing Instantaneous-Opening Envelope, construction of which the following is the specification.

10 Our invention relates to a new form of envelope produced by a combination of flaps and referred to as a selfsealing, instantaneous opening envelope to be used for all classes of mail handled through the United States 15 mails, on which a postage stamp is used.

The envelope is so constructed that it can be made with a less amount of material than the usual and ordinary envelope, and after its manufacture same can be sealed without 20 application of mucilage or other adhesives, except by the application of a postage stamp over a locking device provided for that purpose. These objects are attained by manufacturing the envelope in its completed form 25 which leaves the one end open with main flap extended and ready for the insertion of mail matter; after the insertion of mail matter the main flap is closed over into its natural position and the application of an ordinary postage stamp seals the letter so it cannot be reopened without the removal of the postage stamp, and at the same time affords a means by which the envelope may be instantaneously opened by taking hold of that 30 portion or projection of the main flap which extend from beneath the postage stamp, thereby eliminating the necessity of using a knife or other instrument to open the envelope.

40 We attain these objects by the combination flaps illustrated in the accompanying drawings in which:—

Figure 1, shows the material laid out after being cut and before being folded.

45 Figure 2, shows the envelope with body complete, and open at one end for the reception of mail, main flap extended.

Figure 3, shows the combination flaps of the envelope placed in position and ready to 50 affix stamp.

Figure 4, shows the envelope closed and sealed with the postage stamp affixed.

55 Figure 5, shows the form and back of the envelope, with body flaps sealed. Similar numerals refer to similar parts throughout the several views.

After paper has been cut in its completed form ready for construction of envelope and before folding, we have the following parts described as follows: B indicates front side 60 of the envelope and C folds under on dotted line E, forming the back or reverse side of envelope. Flaps D are extensions of B and are to be pasted down over C with gum or mucilage, thereby forming the pouch for the 65 reception of mail.

Take the open envelope ready for the insertion of letters or other mail matters, insert letter or mail matter at right end of envelope. The process of closing is performed by turning main closing flap A to the left and laying the lower section of this flap A under lower right hand edge of section B where it fits into a V shaped incision at the center of right hand edge of section 70 B prepared for this purpose; this permits the upper portion of main flap A with its projection or neck to lay over the upper right hand part of section B, where the projection or neck fits automatically under 75 the interlocking flaps A'.

These flaps are produced by a double incision made near the upper right hand corner of the surface of envelope, with a cross incision therein forming two small flaps, 80 which will have been pressed out before closing the letter; then close these flaps A', down over the projection or neck of main flap A to hold it firmly in position.

Then by placing the postage stamp over 85 these interlocking flaps A', so that the edge of the postage stamp will be on the line with the left edge of the interlocking flaps and adhering to the surface of flaps A', main flap A and section B effectually self-seals the envelope without mucilage, and the projection or neck of main closing flap A which permits it to extend beyond and to the left of the postage stamp affords a means of instantaneously opening the envelope.

We are aware that prior to our invention and at the present time, envelopes are being constructed of paper cut in a shape that after being folded three flaps lay over and are sealed together on the back side and forms a receptacle for mail matter, leaving the one flap on upper back side of envelope mucilaged and free to seal the receptacle, after insertion of mail matter.

110 We do not claim to have invented the manner of making the pouch or main recep-

tacle of the envelope, but the peculiar means by which the envelope is closed, sealed and opened; and to this end—

We claim:

5. An envelope having front and back walls, a flap extending from one of said walls, said flap having a projection, small flaps formed

in the other of said walls and adapted to overlie the projection of the flap when the flap is folded over said wall to close the envelope. ¹⁰

ARNOLD B. OGDEN.

ERVIN WILLIAM WEIGAND.
